CLAIM

The ornamental design for an allergen test tray cover with a detachable see-through label, as shown and described.

DESCRIPTION

FIG. 1 is a top plan view of the allergen test tray cover with a detachable see-through label, showing my new design; FIG. 2 is a bottom plan view thereof;

FIG. 3 is a front view thereof, the rear view being a mirror image of the front view;

FIG. 4 is a left-side view thereof, the right-side view being a mirror image of the left-side view;

FIG. 5 is a perspective view thereof; and,

FIG. 6 is a sectional view taken along line 6-6 in FIG. 1. The broken lines depict portions of the allergen test tray cover with a detachable see-through label.

1 Claim, 5 Drawing Sheets
